UNITED STATES PATENT OFFICE.

JOSEPH BERGER, OF UTICA, NEW YORK, ASSIGNOR TO UNION SPECIAL MACHINE COMPANY, OF CHICAGO, ILLINOIS, A CORPORATION OF ILLINOIS.

THREAD-CONTROLLING MECHANISM FOR SEWING MACHINES.

Application filed May 31, 1921. Serial No. 473,564.

To all whom it may concern:

Be it known that I, JOSEPH BERGER, a citizen of the United States, residing at Utica, in the county of Oneida, State of New York, have invented certain new and useful Improvements in Thread-Controlling Mechanisms for Sewing Machines, of which the following is a description, reference being had to the accompanying drawing and 10 to the figures of reference marked thereon.

The invention relates to new and useful improvements in thread controllers for sewing machines, and more particularly to a sewing machine for forming triple interconnected covering stitches wherein the needle thread loops are connected at one face of the fabric by a looper thread and at the other face of the fabric by a cross thread.

20 An object of the invention is to provide a machine of the above type with a thread controlling mechanism wherein certain of the threads are positively pulled from the supply and the working slack so taken care of that the resulting seam is substantially uniform throughout its entire extent.

A further object of the invention is to provide a thread controlling mechanism with devices for relieving the stitching threads from undue strain so as to allow the cloth to feed easier and also to increase the elasticity of the covering seam.

30 A still further object of the invention is to provide a thread controlling mechanism for a machine of the above type wherein the cross thread is pulled from the supply in measured amounts preferably when the needles are at the lower ends of their strokes so that the cross thread is relieved from undue strain and, therefore, more uniformly laid about the needle thread loops.

Another object of the invention is to provide a machine of the above type having needles set with their eyes at different 45 heights, with a thread controlling mechanism for supplying thread to the needles in amounts corresponding to the setting of their eyes so that said needles may move to the lower ends of their strokes without placing the threads under undue strain, which thread controlling devices also operate to positively take up some of the slack of the needle threads of the needles having their eyes moving to the greater distance below 55 the fabric so as to insure the forming of

loops in the needle threads for the looper to enter which are sufficiently small whereby they can be controlled.

These and other objects will in part be obvious and will in part be hereinafter more 60 fully disclosed.

In the drawings, which show by way of illustration one embodiment of the invention:—

Figure 1 is a front view of a sewing machine embodying any improvements with the needles at the upper ends of their strokes; 65

Fig. 2 is a similar view, but showing the needles at the lower ends of their strokes; 70

Fig. 3 is a similar view but showing the needles as having slightly retracted and thrown out their respective loops for the looper to enter;

Fig. 4 is a view in top plan of a portion 75 of the machine;

Fig. 5 is an enlarged view of the head of the machine showing the work support and presser foot in section and with the needles at the upper ends of their strokes; 80

Fig. 6 is a similar view, but showing the needles at the lower ends of their strokes;

Fig. 7 is a transverse sectional view through the overhanging arm and point between the pull-off and the thread nippers; 85

Fig. 8 is a perspective view of the releasing member for the nippers, the bracket for supporting the same, and the guide eyes for the cross thread;

Fig. 9 is a perspective view of the bracket 90 carried by the needle arm which operates to actuate the member for releasing the nippers;

Fig. 10 is a perspective view with parts 95 separated showing the tension for the needle threads at the lower end of the needle bar and the eye carried by the needle bar for the cross thread;

Fig. 11 is a perspective view of a portion 100 of the thread controlling devices;

Fig. 12 is a view in side elevation and showing more or less diagrammatically a modified form of the thread controller which permits the amount of thread pulled off for the respective needles to be independently 105 varied;

Fig. 13 is a view similar to Fig. 12, but showing the thread arm at the other end of the stroke; and

Fig. 14 is a perspective view of some of 110

the parts of the thread controlling mechanism, the parts being separated for clearness.

The invention is directed broadly to a thread controlling mechanism for a sewing machine, which sewing machine is preferably provided with three needles with which a single looper cooperates beneath the fabric and with which a single cross thread laying mechanism operates above the fabric. In a machine of this type, it is desirable to place the needles with their eyes at different heights, the needle with its eye set at the lowest point being at the left hand as viewed from the front of the machine when the looper moves into the thread loops from right to left, and the intermediate needle has its eye set a little higher than the eye of the left hand needle and a little lower than the eye of the right hand needle.

Nipper springs are provided for the needle threads which are actuated to clamp and hold the threads from movement while the needles are passing through the lower portions of their reciprocations. There is also provided a pull-off located between the needles and the tensions which operates when the nippers are closed to pull thread from the supply, and these pull-offs are so constructed that a greater amount of thread is pulled off thereby for the left hand needle than is pulled off by the pull-off for the right hand needle, while the amount of thread pulled off for the intermediate needle is slightly less than that pulled off for the left hand needle, and greater than that pulled off for the right hand needle. When the needles move to the upper ends of their strokes and the nippers are open, this slack thread is pulled through the nippers and this enables the needles to move to the upper end of their strokes without putting the threads under undue strain and permits an easy feeding of the fabric and increases the elasticity of the seam. More thread is pulled off for the left hand needle, because the eye of this needle moves a great distance beneath the fabric and, therefore, more working slack is required for this needle. The right hand needle on its up stroke pulls thread through the tension from the supply; this is desirable for the reason that the looper thread and the cross thread are pulled against the right hand needle thread and it should be under slight tension in order to properly make a uniform seam.

Devices are also provided between the nippers and the thread eyes on the needle bar for the left hand needle thread and the thread of the center needle which operate on the first part of the upward movement of the needles to take up some of the slack in the needle threads, and these devices are so arranged that the greater amount of slack is taken up in the left hand needle than the

center needle. By this arrangement, the needle thread loops thrown out by the left hand needle and the center needle are reduced in size so that they are in range of control. The right hand needle loop is relatively small and is first entered by the looper and no means is necessary for taking up the slack. Means is also provided for pulling thread from the supply for the cross thread in measured amounts corresponding to the amount of thread consumed by the seam, and pull-up devices are also provided for pulling up this cross thread so as to lay the thread in measured amounts and thus provide a covering seam of uniform width on the right or face side of the goods.

Referring more in detail to the drawings, I have shown my invention as embodied in a sewing machine consisting of a supporting bed 1 carrying a standard 2 in which is mounted a main shaft 3. Suitably mounted on the standard 2 is an overhanging arm 4 in which a needle bar 5 reciprocates. Said needle bar is reciprocated by a needle lever 6 pivoted at 7 to the overhanging arm 4 and oscillated by an eccentric strap 8 cooperating with an actuating device from the main shaft 3. This needle bar 5 carries three needles 9—10—11. Cooperating with the needles beneath the work support is a thread carrying looper 12.

The work support, indicated at 13 in the drawings, is in the form of an arm which projects horizontally and rearwardly from a standard 14 carried in turn by a laterally projecting arm 15 mounted on the bed 1. The looper is oscillated and moved laterally by a suitable train of mechanism located in the arm 13, standard 14, arm 15 and main standard 2. The material is fed across the work support by means of a feed dog 16. The material is held on the work support by means of a presser foot 17. These parts are of the usual construction and it is not thought that further description thereof is necessary.

For the purpose of description, the needle 11 will be referred to as the left hand needle, as it is at the left as viewed by the operator, while the needle 9 will be referred to as the right hand needle, and the needle 10 as the center needle. It is understood, of course, that the looper 12 cooperates with all three needles, entering first the needle thread loop of the right hand needle, then the needle thread loop of the center needle, and then the needle thread loop of the left hand needle. It will be noted from Figs. 1, 5, and 6 that the eye 18 of the left hand needle is set at a different height than the eye 19 of the right hand needle, while the eye 20 of the center needle is still at another height, the eye of the left hand needle being the lowest and will move the greatest distance beneath the fabric. The eye of the

right hand needle will move the least distance beneath the fabric.

The needle threads for the needles 9, 10 and 11 are indicated, respectively, at *a*, *b* and *c*. These needle threads pass from the supply through suitable tensions 21, thence through suitable guide eyes in a supporting bracket 22. The needle threads then pass through suitable eyes in an arm 23, and thence through nippers 24, one for each thread. The threads *c* and *b* of the left hand needle and center needle, respectively, then pass through a light tension 25, while the needle thread *a* does not pass through this tension but through an eye 27 carried by an arm 26. The three needle threads then pass through eyes in an arm 28 secured to the upper end of the needle bar 5. The needle threads then pass down along side of the needle bar underneath a tension plate 29 through the slot in the needle holder, and then to the eyes of the needles.

The looper thread is indicated at *l* in the drawings. This looper thread passes from the supply through a tension 30, thence underneath the guide plate 31 to a thread controlling mechanism 32, and thence through the arm 15 to a thread guiding tube 33 and through suitable guides to the looper. The cross thread for connecting the needle thread loops on the upper surface of the fabric is indicated at *d*. This cross thread is passed from the supply through a suitable tension 34, thence to an eye 35 in an arm 36, thence to an eye 37 in said arm, and then through one of the nippers 24 to a guide eye 38, and then through a guide eye 39 carried by the needle bar to a guide eye 40, and to the cross thread laying mechanism which is herein shown in the form of a hook 41 which engages the cross thread and forms it into a loop for the left hand needle to enter.

The particular form of cross thread laying mechanism is immaterial and forms no part of the present invention except in the general combination of the parts. This cross thread laying mechanism preferably includes, however, a thread hook which forms the cross thread into a loop, and then releases the loop, and a cooperating thread finger which engages one strand of the cross thread and carries it rearwardly so as to place it properly for the needles to pass, so that the cross thread will extend back and forth across the seam encircling the needle thread loop first at one side of the seam and then at the other side of the seam, and all of the needle thread loops in the outer rows will be encircled.

The thread nippers are controlled by a pivoted lever 42 which is provided with a yoke having upwardly extending arms 43-43 which are adapted to engage the head 44 of the rod upon which the nipper disks are placed, and when moved toward

the operator, as viewed in Fig. 4, said rod is moved so as to compress spring 45 and release the nipper disks from their grip upon the threads, and thus the threads are permitted to run free through the nippers. This pivoted lever 42 is operated by a plate 46 adjustably carried by a bracket 47 which is secured to the needle lever 6 by means of a screw 48. This adjustable plate 46 engages a wedge-shaped member 49 carried at the lower end of the lever 42.

It will be apparent from the drawings that, when the needle lever is raised and the needles are at the upper ends of their strokes, this plate 46 will engage the wedge-shaped member 49 and swing the lever 42 so as to pull forward on the rod carrying the nippers, compressing the spring 45 and releasing the nippers from tension so that the threads run free. When the needle lever is at the lower end of its stroke, the lever 42 will be released and the nippers, through the action of the spring 45, will be caused to grip the three needle threads and the cross thread and hold the same from movement. These nippers for the needle threads per se form no part of the present invention, and it is obvious that other forms of nippers may be used, the essential feature being that the threads shall be clamped and held from movement while the needles are passing through the lower portions of their strokes and the threads shall be released and free when the needles are passing through the upper portions of their strokes.

As above noted, the three needle threads pass through suitable eyes formed in the arm 23. This arm 23 extends through a lug 50 carried by the bracket 47 and is held in adjustable positions therein by means of a set-screw 51. The arm 23 will, therefore, move up and down with the needle lever and will move toward and from a straight line connecting the nippers with the guide eyes in the bracket 22. Thus the arm 23 will pull on the needle threads and will pull the thread through the tensions from the supply as said arm operates to pull on the threads when they are clamped by the nippers. It will be noted that the eye 52 at the outer end of the arm 23, and through which the needle thread *c* passes, is higher than the eye 53 through which the needle thread *b* passes, and this eye 53 is also higher than the eye 54 through which the needle thread *a* passes.

By this arrangement of the eyes 52, 53 and 54, I pull off more of the needle thread *c* than the needle thread *b*, and also more of the needle thread *b* than the needle thread *a*. The reason for pulling off these different amounts in the three needle threads is because of the setting of the eyes of the needles at different heights, as above described; the eye of the left hand needle

passing a greater distance beneath the fabric requires more thread than either of the other needles wherein the eyes pass a less distance beneath the fabric, without putting the thread under undue strain which might cause the needle to cut through or break the thread. The thread which is pulled off by this rod 23, which I shall refer to as constituting a pull-off for the needle threads, is carried through the nippers when the nippers are open by the upward movement of the needle bar and the looper taking the threads and, of course, will be given up to the needles on the next descent 15 of the needle bar.

When the needles start to rise, they throw out their needle thread loops for the loopers to enter in the well-known manner, and it will be obvious that the left hand needle, 20 whose eye moves to a greater distance beneath the fabric, would naturally form a larger needle thread loop. If the needle thread loop is very large, it becomes uncontrollable, thereby causing the looper to 25 skip the loop and thus skip a stitch. In order to prevent this undue enlargement of the needle thread loops of the left hand and center needles, I have provided the tension device 25.

30 This tension device consists of a plate mounted on a screw 55 carried by a bracket 56 which in turn is mounted on an arm 57 carried by a supporting member 58 which in turn is secured to the needle lever 6 by 35 screws 59—59. Said arm 57 is clamped to the member 58 by a set-screw 60. A suitable spring encircles the screw 55 and causes the plate to yieldingly clamp the threads *c* and *b* against the bracket arm 56.

40 As the needle lever oscillates, rod 57 will be moved toward and from the needle bar and as it moves toward and from the needle bar, the angular position of the tension 25 and also the rod 57 relative to the vertical or 45 the axis of the needle bar will be changed. This movement of the tension 25 away from the needle bar causes the needle threads *c* and *b* to be pulled up, and this reduces the needle thread loops thrown out by the needles 11 and 10 so that they may be well within control. In view of the fact that the 50 angular position of the rod 57 changes, there will be more slack taken up in the needle thread *c* than in the needle thread *b*.

55 This is desirable for the reason that the eye of the center needle does not move so far beneath the fabric as the eye of the left hand needle and, of course, it is not desirable to take up so much of the thread of the center needle as is taken up for the thread of the left hand needle. The needle thread *a*, as above noted, passes through the eye 27 in the arm 26. This arm 26 is also carried 60 by the supporting member 58 and is held 65 thereon by a set-screw 61. The eye 27 will

move up and down with the needle bar and assist in taking care of the slack, but inasmuch as the thread *a* moves freely through the eye 27, the needle thread *a* will not be drawn back on the first part of the upward 70 movement of the needles. It is not necessary, nor desirable, to take up the needle thread loop of the right hand needle; the loop of this needle thread will take care of itself on account of the point of the 75 looper getting into it very early in its forward movement.

As the needle bar reaches the upper end of its stroke, the slack pulled off from the supply by the pull-off will be drawn 80 through the nippers, a sufficient slack being given to the needle threads *c* and *b* so that there is little or no strain on the fabric and this allows the fabric to feed through freely and also increases the elasticity of the 85 stitches being formed. The slack in the needle thread *a*, however, is all consumed before the needle bar reaches the upper end of its stroke, and a certain amount of 90 thread will be pulled through the tension from the supply by the upward movement 95 of the needle bar for this needle thread *a*. This puts the needle thread *a* under tension which is very desirable for the reason 100 that the looper in moving to the forward end of the stroke, which it reaches approximately at the time the needle bar reaches the upper end of its stroke, draws the looper thread running to the previous stitch against the right hand needle thread loop. The cross thread laying hook also draws the cross thread running to the previous 105 stitch against the right hand needle thread, and in order to keep the seam uniform, it is desirable to have this needle thread *a* under 110 slight tension at this time. This is accomplished by reason of the fact that the pull-off, owing to the setting of the eyes, does not pull off quite enough thread for the right hand needle so that the needle bar 115 pulls off the rest of the thread necessary for this right hand needle.

The cross thread *d*, as above noted, passes through thread eyes 35 and 37 in the arm 36. This arm 36 is secured by a set-screw 62 to a sleeve 63 which is formed as part of a bracket 64 fixed to the overhanging arm 4 by screws 65—65. The arm 23 oscillates back and forth between the eyes 35 and 37 120 and will engage the cross thread and pull a measured amount of cross thread from the supply. This amount may be varied by varying the position of the eyes 35 and 37 through the shifting of the arm 36 back and forth in its supporting sleeve 63. The cross thread is, of course, pulled from the supply when the nippers are closed. A cross thread laying hook moves forward to form a loop in the cross thread when the needles are 125 raised and when the nippers are open, and 130

this measured amount of thread is given up to the cross thread laying hook so that the loop may be formed without exerting undue strain of the cross thread on the previously 5 formed stitches. This again reduces the strain on the threads and the fabric, allowing the fabric to feed free and easy. It also increases the elasticity of the stitch as the threads are not under undue strain when 10 the stitches are set.

It will be readily seen that, if there is no pull-off for the cross thread, then the cross thread laying hook must pull the thread from the supply through the tension and 15 this causes the cross thread to drag on the needle threads and results in a more or less non-uniform width of cross stitches, but by my improved thread controlling mechanism, wherein there is a measured amount of cross 20 thread pulled from the supply and given up as slack to the cross thread laying mechanism, just the right amount of thread may be supplied without putting any strain on the cross thread, and thus a uniform laying 25 of the cross thread will be insured. On the downward movement of the eye 39 on the needle bar, the slack in the cross thread will be taken up and the cross thread will be pulled snug around the needles, the thread 30 being held at this time by the nippers, and this pulling of the cross threads when gripped and around the needles further insures a uniform width of cross thread stitch. The thread *a* of the right hand needle en- 35 gages a post 66 on the descent of the needles, which puts the right hand thread under slight strain just before the needle reaches the lower end of its stroke, and this aids in the quickly throwing out of the needle 40 thread loop on the upper movement of the needle. This is a well-known feature in the art and forms no part of the present invention.

The operation of the device is thought 45 apparent from the above description: The thread controlling mechanism operates to pull thread from the supply for the three needles and in different amounts, according to the setting of the eyes of the needles, and 50 this slack thread pulled from the supply is given to the needles so that, as they pass through the fabric, there will be sufficient thread to permit the needles to move to the lower ends of their strokes without undue 55 strain on the threads and possible breaking thereof. On the first part of the upward movement of the needles, a portion of the thread of the left hand needle and center needle is taken up so as to reduce the size 60 of the needle thread loops drawn out by these needles and keep the same within control so as to avoid the skipping of the loops by the looper. As the needles reach the upper ends of their strokes, the slack pulled 65 off by the pull-off is pulled through the

nippers and the amount of slack pulled off for the right hand needle is slightly less than necessary for the working stroke of the right hand needle so that the needle thread of this right hand needle will be placed under 70 tension when the needle bar reaches the upper end of its stroke, which is a very desirable condition owing to the fact that the cross thread and the looper thread are at this time necessarily drawn against the thread of 75 the right hand needle.

At times it may be desirable to vary independently the amount of thread pulled off for the respective needles. In Figs. 12 and 13 of the drawings, I have shown a 80 modified form of structure which permits this to be accomplished. The threads *a*, *b* and *c* pass from the supply through independent thread eyes 70^a in the rod 70. This rod 70 is a substitute for the rod 23 shown in the other figures of the drawings and differs therefrom merely in shaping, the upper end of the rod being substantially horizontal instead of inclined upwardly. The thread *c* is then led to a thread finger 71; the thread *b* to a thread finger 72, and the thread *a* to a thread finger 73. The bracket 63 is provided with an extension 74, and these three fingers 71, 72 and 73 are mounted in the extension 74 and clamped 85 therein by independent set-screws 75. By loosening the set-screw holding the finger 71, it may be adjusted endwise in the extension 74; the same is true of the other thread fingers. These thread fingers are provided 90 with a thread eye through which the respective threads pass, and from these fingers the threads are led to the nippers 24.

The operation of the modified device is precisely as described above in connection 105 with the thread arm 23, the only difference being that the thread fingers may be adjusted so as to vary the position of the thread eyes carried thereby, and this will vary the extent of movement of the arm 70 110 relative thereto and in turn vary the amount of thread pulled off for the respective needles. While I have stated that the modified form of device operates precisely as described in connection with the thread arm 23, there is, however, this slight difference: The amount of thread pulled off by the thread eye 70^a at the end of the arm 70 in the modified form differs from the 115 amount of thread pulled off for the other thread eyes in this arm by reason of the fact that the thread fingers 71, 72 and 73 are set so as to extend different distances from the supporting extension 74, and it is by the setting of these fingers that the amounts pulled off of the several threads are different and by adjusting the fingers the amounts may be independently varied.

It will also be noted that the improved 120 thread controlling mechanism pulls off a 125

measured amount of thread for the cross thread laying hook which is given thereto when it moves forward so that the cross thread is comparatively free from undue strain as well as the needle thread of the left hand needle and the center needle at the time when the feed takes place, and this permits very easy feeding of the fabric without straining the threads and results in a very elastic covering seam. The thread eyes for the cross thread are so related to each other as to take up the slack in the cross thread, drawing it snugly about the needles when the needles are at the lower ends of their strokes and this results in a cross stitch of uniform width.

It is obvious that minor changes in the details of construction and the arrangement of parts may be made without departing from the spirit of the invention as set forth in the appended claims.

Having thus described the invention, what is claimed as new is:

1. The combination with a covering stitching mechanism including a plurality of needles having the eyes thereof set at different heights, and a threaded looper cooperating with said needles at one face of the fabric being stitched, of a thread controlling mechanism including means for pulling different amounts of the respective needle threads from the supply proportionate to the distance between the eyes of the respective needles and the fabric, and means operating upon the thread of the needle having the lowest set eye for taking up thread on the first part of the upward movement of the needle to reduce the size of the needle thread loop thrown out for the looper to enter.

2. The combination with a covering stitching mechanism, including a plurality of needles having the eyes thereof set at different heights, a threaded looper cooperating with said needles at one face of the fabric being stitched, and a cross thread laying mechanism cooperating with said needles at the other face of the fabric, of a thread controlling mechanism including means for pulling different amounts of the respective needle threads from the supply proportionate to the distances between the eyes of the respective needles and the fabric, and means operating upon the thread of the needle having the lowest set eye for taking up thread on the first part of the upward movement of the needle to reduce the size of the needle thread loop thrown out for the looper to enter.

3. The combination with a covering stitching mechanism, including a plurality of needles having the eyes thereof set at different heights, a threaded looper cooperating with said needles at one face of the fabric being stitched, and a cross thread

laying mechanism cooperating with said needles at the other face of the fabric, and a thread controlling mechanism including tension devices, thread nippers, and pull-off means operating upon the needle threads between the tensions and nippers for pulling different amounts of the respective needle threads through the tensions when the nippers are closed proportionate to the distances between the eyes of the respective needles and the fabric.

4. The combination with a covering stitching mechanism, including a plurality of needles having the eyes thereof set at different heights, a threaded looper cooperating with said needles at one face of the fabric being stitched, and a cross thread laying mechanism cooperating with said needles at the other face of the fabric, and a thread controlling mechanism including tension devices, thread nippers, pull-off means operating upon the needle threads between the tensions and nippers for pulling different amounts of the respective needle threads through the tensions when the nippers are closed proportionate to the distances between the eyes of the respective needles and the fabric; and means operating upon the needles having the lowest set eyes and between the eyes and the nippers for taking up the threads on the first part of the upward movement of said needles to reduce the size of the needle thread loops thrown out thereby for the looper to enter.

5. The combination with a work support and covering stitching mechanism including three needles having the eyes thereof set in a line inclined relative to the plane of the work support, a threaded looper arranged to enter first the thread loop of the needle having its eye set the highest, subsequently the thread loop of the center needle, and then the thread loop of the other needle, a cross thread laying mechanism, and a thread controlling mechanism including means for pulling different amounts of the respective needle threads from the supply proportionate to the distances between the eyes of the respective needles and the fabric, and means operating upon the thread of the needle having the lowest set eye for taking up the thread on the first part of the upward movement of the needle to reduce the size of the needle thread loop thrown out for the looper to enter.

6. The combination with a work support and covering stitching mechanism including three needles having the eyes thereof set in a line inclined relative to the plane of the work support, a threaded looper arranged to enter first the thread loop of the needle having its eye set the highest, subsequently the thread loop of the center needle, and then the thread loop of the other needle, a cross thread laying mechanism, and a thread

controlling mechanism including means for pulling different amounts of the respective needle threads from the supply proportionate to the distances between the eyes of the 5 respective needles and the fabric, and means operating upon the threads of the needles having the lowest set eyes for taking up the threads thereof on the first part of the upward movement of the needles to reduce the 10 size of the needle thread loops thrown out for the looper to enter.

7. The combination with a work support and covering stitching mechanism including three needles having the eyes thereof set in 15 a line inclined relative to the plane of the work support, a threaded looper arranged to enter first the thread loop of the needle having its eye set the highest, subsequently the thread loop of the center needle, and 20 then the thread loop of the other needle, cross thread laying mechanism, and vibrating means operating upon the threads of the needle having the lowest set eye and the center needle independent of the thread of 25 the needle having the eye set highest for taking up the threads of the needle having the lowest set eye and the center needle on the first part of the upward movement of the needles to reduce the size of the needle 30 thread loops thrown out by the needle having the lowest set eye and the center needle for the looper to enter.

8. The combination with a work support and covering stitching mechanism including 35 three needles having the eyes thereof set in a line inclined relative to the plane of the work support, a threaded looper arranged to enter first the thread loop of the needle having its eye set the highest, subsequently 40 the thread loop of the center needle, and then the thread loop of the other needle, cross thread laying mechanism, and vibrating means operating upon the threads of the 45 needle having the lowest set eye and the center needle for taking up the threads thereof on the first part of the upward movement of the needles to reduce the size 50 of the needle thread loops thrown out by the needle having the lowest set eye and the center needle for the looper to enter, said means for taking up the threads being constructed so as to take up more thread for the needle of the lowest set eye than for the center needle.

9. The combination with covering stitching mechanism including three needles with their eyes set in a line inclined to the path of reciprocation of the needles, a needle lever for reciprocating the needles, means 55 carried by the needle lever for engaging the needle threads for pulling thread from the supply proportionate to the distance between the eyes of the needles and the fabric, and means carried by the needle lever for 60 engaging the thread of the needle having

the lowest set eye and the thread of the center needle and operating to take up the needle threads on the first part of the upward movement of the needle lever in different amounts proportionate to the distance 70 between the eyes of the needles and the fabric.

10. The combination of covering stitching mechanism including a plurality of needles having their eyes set in a line inclined to 75 the path of reciprocation of the needles, a needle bar carrying said needles, a needle lever for reciprocating said bar, thread nippers through which the needle threads pass, means actuated by the needle lever for releasing the nippers when the needles are at the upper ends of their strokes, tension devices through which the threads pass, a pull-off arm carried by the needle lever and located between the thread nippers and the 80 supply, said arm having a separate eye for each thread, thread guides associated with said pull-off arm, said eyes and thread guides being set at different distances from each other and engaging the thread so that a 85 greater amount of thread is pulled off for the needle having its eye set in the lowest position, a less amount of thread for the center needle, and a less amount of thread for the needle having its eye set highest, a 90 thread carrying looper adapted to enter first the thread loop of the needle with the highest set eye, and then the other thread loops of the needles.

11. The combination of covering stitching mechanism including a plurality of needles having their eyes set in a line inclined to 100 the path of reciprocation of the needles, a needle bar carrying said needles, a needle lever for reciprocating said bar, thread nippers through which the needle threads pass, means actuated by the needle lever for releasing the nippers when the needles are at the upper ends of their strokes, tension devices through which the threads pass, a pull-off arm carried by the needle lever and having a separate eye for each thread, thread guides associated with said pull-off arm, said 105 eyes and thread guides being set at different distances from each other and engaging the thread so that a greater amount of thread is pulled off for the needle having its eye set in the lowest position, a less amount of thread for the center needle, and a less amount of thread for the needle having its eye set highest, a 110 thread carrying looper adapted to enter first the thread loop of the needle with the highest set eye, and then the other thread loops of the needles, an arm carried by the needle lever between the nippers and the needle bar, a tension plate carried by the arm and adapted to engage the thread of the needle with the lowest set eye and the thread of the center needle, said 115 tension plate being adapted to swing with 120 the needle lever.

the needle lever and take up the needle threads on the first part of the upward movement of the needles so as to reduce the size of thread loops thrown out for the 5 looper to enter.

12. The combination of covering stitching mechanism including a plurality of needles, having their eyes set in a line inclined to the path of reciprocation of the needles, a 10 needle bar carrying said needles, a needle lever for reciprocating said bar, thread nippers through which the needle threads pass, means actuated by the needle lever for releasing the nippers when the needles are 15 at the upper ends of their strokes, tension devices through which the threads pass, a pull-off arm carried by the needle lever and having a separate eye for each thread, thread guides associated with said pull-off arm, 20 said eyes and thread guides being set at different distances from each other and engaging the thread so that a greater amount of thread is pulled off for the needle having its eye set in the lowest position, a less 25 amount of thread for the center needle, and a less amount of thread for the needle having its eye set highest, a thread carrying looper adapted to enter first the thread loop of the needle with the highest set eye, and 30 then the other thread loops of the needles, said pull-off being so proportionated that the amount of thread pulled off for the needle with the lowest set eye and the center needle is sufficient to allow the needles to move 35 to the upper ends of their strokes without putting the threads under tension while the thread supply to the needle with the eye set high is insufficient for the needle to move to the upper end of its stroke so that the

needle bar pulls off thread from the supply 40 for said needle and thus places said thread under tension.

13. The combination with covering stitching mechanism including a plurality of needles, complemental stitch forming mechanism cooperating with the needles at one face of the fabric and a cross thread laying mechanism cooperating with the needles at the other face of the fabric, of a thread npper for the cross thread adapted to grip 45 the thread when the needles are at the lower ends of their strokes, a tension device for the cross thread, means operating upon the cross thread between the tension and the nippers for pulling a measured amount of 50 cross thread from the supply, and means for taking up the cross thread and drawing the same around the needles when the needle needles are in the fabric.

14. The combination with covering stitching mechanism including a plurality of needles having the eyes thereof set at different heights, a threaded looper cooperating with said needles at one face of the 60 fabric being stitched, a cross thread laying mechanism cooperating with said needles at the other face of the fabric, of a thread controlling mechanism including means for pulling different amounts of the respective 65 needle threads from the supply proportionate to the distances between the eyes of the respective needles and the fabric, and means whereby the amount of thread pulled off for the respective needles may be independently varied.

In testimony whereof I affix my signature.

JOSEPH BERGER.
